UNITED STATES PATENT OFFICE.

YAN PHOU LEE, OF PHILADELPHIA, PENNSYLVANIA.

FOLDING GO-CART.

SPECIFICATION forming part of Letters Patent No. 633,141, dated September 19, 1899.

Application filed May 2, 1899. Serial No. 715,300. (No model.)

To all whom it may concern:

Be it known that I, YAN PHOU LEE, a subject of the Emperor of China, residing at Philadelphia, in the county of Philadelphia 5 and State of Pennsylvania, have invented a certain new and useful Improvement in Folding Go-Carts or Perambulators, of which the following is a specification.

My invention relates to a new and useful 10 improvement in folding go-carts or perambulators, and has for its object to provide an exceedingly simple and effective device of this description which when adjusted for use will be as rigid and convenient as if of ordinary construction, and yet when not desired for use it may be collapsed into an exceedingly 15 small compass, whereby it may be readily stored or transported from one place to another, thus providing for the carrying of the 20 cart to picnics, excursions, and the like without material inconvenience.

With these ends in view this invention consists in the details of construction and combination of elements hereinafter set forth and 25 then specifically designated by the claims.

In order that those skilled in the art to which this invention appertains may understand how to make and use the same, the construction and operation will now be described in 30 detail, referring to the accompanying drawings, forming a part of this specification, in which—

Figure 1 is a perspective of a cart made in accordance with my improvement in adjustment for use; Fig. 2, a central section thereof; Fig. 3, a view showing the cart folded; and Fig. 4, a section of Fig. 3, showing the relative position of the various parts when folded.

In carrying out my invention as here embodied, A represents the back of the perambulator, which is in the form of a chair, and to this back is hinged the bottom or seat B, as indicated at C, so as to fold upward and inward and against the back.

45 D are clips secured to the back, and to which are pivoted the arms E of the perambulator in order that the arms may swing horizontally and inward, as will be hereinafter set forth, and the outer ends of these arms have hinged 50 thereto at F the front legs G. The side rails of the back have hinged to their lower ends at H the rear legs I in such manner that said

legs may be swung backward and upward against the rear of the back and when in position are held in adjustment by the snap-springs J. The front and rear legs are connected and braced by the rods K, upon the ends of which are formed hooks to engage suitable eyes attached to the legs. Each pair of legs is braced sidewise by the rods L, 60 which are likewise hooked into eyes attached to the legs. This arrangement forms a four-way brace and ties the legs together when in adjustment, so as to render them rigid.

Caster-wheels M are journaled in the lower 65 forked ends of the legs G, and the casters N are journaled in the extensions O of the legs I, and these extensions have shanks, preferably secured in cross-section, which enter into suitable sockets formed in the legs I, whereby 70 they are held in any adjustment by the set-screws P.

Q represents the foot-board, which is hinged at R to the front board S, the latter in turn being hinged at T to the seat B, whereby these 75 members may be folded one upon the other, as will be hereinafter set forth.

U represents the handles which are jointed at V and attached at U to the side rails of the back. These handles are held in proper 80 position when in active adjustment by the toggle-joints X, which lock them in the positions shown in Figs. 1 and 2, or permit them to be folded in the position shown in Fig. 4.

From this description it will be obvious 85 that the go-cart when adjusted for use will be as rigid as a go-cart of ordinary construction, and yet when it is desired to collapse the same it is only necessary to fold the foot-board against the front board S and swing 90 the seat upward against the back and the front board against the bottom thereof, when by removing the rods K and L the front legs may be swung upward against the arms and the latter turned inward against the foot-board. The rear legs by unlatching the snap-springs J may be folded against the rear of the back and the handles swung inward against said back. When the go-cart is in this condition, the various parts thereof may 100 be held by passing a strap around the same, and, if desired, the safety-strap Y, used to retain the occupant of the chair in position, may be used for this purpose.

Of course I do not wish to be limited to the exact details of construction here shown, as these may be varied to a certain extent without departing from the spirit of my invention—⁵ as, for instance, suitable springs may be interposed between the seat and the frame, so as to give a resilient action, or such spring may be interposed between the caster-forks and the legs, which would effect the same ¹⁰ result.

Having thus fully described my invention, what I claim as new and useful is—

1. A go-cart or perambulator consisting of a back, rear legs hinged thereto, a seat also ¹⁵ hinged to the back, arms pivoted to the back so as to swing sidewise, a front board hinged to the seat, a foot-board hinged to the front board, front legs hinged to the lower ends of the arms, stay-rods for connecting the legs ²⁰ and holding them in adjustment, caster-rolls journaled in the lower ends of the legs, and suitable handles adapted to fold against the back, as specified.

2. A collapsible go-cart consisting of a back,

a seat hinged thereto, a front board hinged ²⁵ to the seat, a foot-board hinged to said front board, said members being adapted to fold against the back, arms pivoted to the back so as to fold inward against the foot-board, legs hinged to the arms, caster-rolls journaled in the lower ends of these legs, a pair ³⁰ of legs hinged to the back, adjustable extensions fitted within sockets formed in the last-named legs, set-screws for holding said extensions in position, caster-rolls journaled in the extensions, means for holding the legs rigidly in position, jointed handles attached to the back, and toggle-joints so arranged as to hold the handles in proper adjustment to permit them to be folded, as shown and de- ³⁵ scribed.

In witness whereof I have hereunto affixed my signature in the presence of two subscribing witnesses.

YAN PIIOU LEE.
